CRANE PLATFORM

Bronislaus Ulinski, Chicago, Ill., assignor to The
Yale & Towne Manufacturing Company, Stamford,
Conn., a corporation of Connecticut

Application February 17, 1943, Serial No. 476,153

8 Claims. (Cl. 212—49)

This invention relates to a platform of the skid or pallet type adapted for cooperation with an industrial lift truck.

Those skilled in the art are fully aware of the extensive use of skids and pallets in the supporting of loads to be moved by industrial lifting trucks. Thus, a load is usually deposited on a skid or pallet, and the lifting portion of an industrial truck is then placed under the floor of the skid, or between the floors of the pallet. Thereafter the skid or pallet is lifted with the load as the lifting portion of the truck is elevated.

There are certain types of loads that are so positioned or must be so deposited, or are so formed, as to make it difficult for those loads to be placed on a skid platform for handling in the usual manner that I have herein briefly outlined. In this class are loads that are best handled by cranes through lifting cables and lifting hooks. In those industrial plants where a considerable number of such loads are to be handled, it is frequently economical to purchase and use a crane truck. In most plants it is not economical to have available a crane truck, and it is therefore extremely difficult in such plants to handle loads of the particular class indicated.

My invention relates to a type of pallet or skid that is constructed to handle loads of the type best handled by a crane. As one feature of my invention through which the several desirable results required thereof are obtained, a crane is mounted for pivotal movement on a support that is integral with a skid or pallet so that as the skid or pallet is elevated by a lift truck the crane will be elevated as though it were part of the lift truck per se.

As a further feature of my invention the crane is adapted for pivotal movement under the influence of the load, and as still a further important feature of my invention this pivotal movement will bring about a counterbalancing of the load carried by the crane whereby to relieve the supporting pallet and the lift truck itself, of those forces tending to tip the pallet and truck.

As still a further feature of my invention, there are means for measuring the amount of movement required to counterbalance the load and thereby to indicate the weight of the load. As still a further feature of my invention, the crane and its counterbalancing mechanism are all rotatable relatively to the pallet whereby to bring the load into a better position for transportation by the truck.

I have thus described generally the several more important features of my invention in order that the construction of my invention hereinafter set forth in detail may be better understood. Naturally, there are certain additional features that I have not thus far described but which will be presented in the specification that follows, and which will be claimed in the claims appended hereto. Those skilled in the art will also appreciate that

5 my invention is a very broad and important one, and that the claims to be granted me should be of such nature as to prevent the utilization of my invention by others in specific forms different from the particular form I shall herein describe.

10 15 Referring now to the drawings,

Fig. 1 is a vertical view showing a pallet embodying my invention and with the lifting forks of a lift truck positioned between the floors of the pallet.

20 Fig. 2 shows the parts of Fig. 1 with the load elevated somewhat and with the crane moved on its pivot to counterbalance the load.

Fig. 3 is a plan view of certain of the parts of Figs. 1 and 2.

25 Fig. 4 is an end view of the crane and pallet assembly looking towards that assembly from the left in Fig. 1.

Fig. 5 illustrates the means whereby the crane is rotatable relatively to the pallet and may be 30 locked in any one of its rotated positions.

Referring now more particularly to the drawings, and especially Figs. 1, 2 and 4, I show my invention applied to a platform of the pallet type as distinguished from the skid type. Those skilled 35 in the art will readily appreciate that my invention is applicable to a skid if that may be desirable. The upper floor of the pallet is designated by reference numeral 10 while the lower floor is designated by reference numeral 11. The 40 floors are held in spaced assembled relation by a series of spacer members 12, 13 and 14 that are welded to the upper and lower floors in a standard manner. Extending between the floors 10 and 11 is a tubular reinforcing member 15 that is welded 45 to the said floors as shown in the drawings. The tubular member 15 protrudes upwardly and into a tubular standard 16 that extends upwardly from the floor 10 of the pallet. For holding the standard 16 in proper relation to the pallet, I employ a channel member 17 that is welded to the standard 16 and the pallet floor 10, and a pair of gusset plates 18 and 19 also welded to the standard 16 as well as to the channel member 17 as will be quite apparent from the drawings.

50 55 It may be well to indicate that the manner in

which the parts are constructed and the method of fabrication and material used, are of no particular importance as my invention relates to the general combination I disclose rather than to the mechanical construction of the parts.

Rotatably mounted on the standard 16 is what I call a crane support 20. This crane support is hollow, as best illustrated in Fig. 5 and is adapted for mounting on the upper end of the standard 16 and for rotation relatively to that standard through an upper bearing 21 and a lower bearing 22. The threaded cap 23 is adapted for insertion on the internal threads 24 of the support 20, and cooperates with the outer race 21a of the bearing 21, it being apparent that in this manner the vertical thrust of the crane support 20 is accepted by the standard 16.

The crane support 20 has an abutment 25 formed thereon and in this abutment is mounted for sliding movement a plunger 26 to the upper end of which is secured a button 27. A spring 28 tends to project the head 29 of the plunger 26 into a hole 30 in a disk 31 welded to the standard 16. As may readily be seen from Fig. 3 there are several of these holes 30 so that the crane support 20 may be locked in any one of a series of different rotated positions relatively to the standard 16 and the pallet to which the standard is welded.

The crane is designated generally by reference numeral 35, and is best shown in Figs. 4 and 5 as pivoted relatively to the crane support 20 on a shaft 36, the said shaft being mounted in ears 37 of the crane support 20 and extending into bores 38 of the arms 39 of the crane 35. To each of the arms 39 there is secured through bolts 40 a bracket 41 formed integrally with a counter weight 42. The opposite ends of the arms 39 of the crane 35 are connected by a bolt 43 that supports a load hook 44.

As is quite apparent from Fig. 1, the load hook 44 may, through a cable 45 and a further hook 46, engage a suitable cable 47 for lifting a load 48. With the parts in the particular position indicated, the forks 49 or other similarly acting parts of an industrial truck T may be inserted under the upper floor 10 of the pallet and then elevated from the position of Fig. 1 to the position of Fig. 2. The load 48 will of course then be elevated also to the position shown in Fig. 2. It will be noted that with the load elevated as shown in Fig. 2, the crane 35 has moved pivotally about the shaft 36 so as to bring the pair of counterbalancing weights 42 into counterbalancing position. It will now be readily appreciated that any tendency for the load 48 to tilt the truck and the pallet has been fully overcome by the movement of the counterbalancing weights 42. It will also be readily appreciated that by withdrawing the head 29 of the plunger 26 from the particular hole 30 in which it is fitted in Fig. 2, the crane support 20 may be rotated to bring the crane and the load into a different position relatively to the lifting truck, and when in that different position the load will remain balanced for movement with the truck.

As a feature of my invention, the weight of the load may be readily determined by mounting a scale 50 on the crane support 20, and placing an indicator 51 on one of the arms 39 of the crane. It is obvious that when the crane moves from the position of Fig. 1 to the position of Fig. 2, the indicator finger 51 will move relatively to the dial 50 a distance proportionate to the weight of the

load 48, thereby making it possible to determine the load.

I believe that the construction and operation of my invention and its great utility in the art 5 will now be clearly understood.

I now claim:

1. In a platform of the class described, a frame structure into which is adapted to enter the lifting mechanism of an industrial truck for lifting 10 said frame structure, a crane support extending vertically from said frame structure, a crane pivoted relatively to said crane support on a horizontal pivot carried by said crane support and having a load supporting arm at one side of its 15 pivot relatively to said crane support, and a counterbalancing weight secured to said crane at the other side of its pivot relatively to said crane support for counterbalancing a load on said load supporting arm.
- 20 2. In a platform of the class described, a frame structure into which is adapted to enter the lifting mechanism of an industrial truck for lifting said frame structure, a crane support extending vertically from said frame structure, a crane pivoted relatively to said crane support on a horizontal pivot carried by said crane support and having a load supporting arm at one side of its 25 pivot relatively to said crane support, and a counterbalancing weight secured to said crane at the other side of its pivot relatively to said crane support for counterbalancing a load on said load supporting arm, said crane pivoting freely on said pivot until the load and counterbalancing weight are brought into balance.
- 30 3. In a platform of the class described, a frame structure into which is adapted to enter the lifting mechanism of an industrial truck for lifting said frame structure, a standard extending vertically from said frame structure, a crane support 35 mounted on said standard for rotation on a vertical axis, and a crane pivoted relatively to said crane support on a horizontal pivot carried by said crane support.
- 40 4. In a platform of the class described, a frame structure into which is adapted to enter the lifting mechanism of an industrial truck for lifting said frame structure, a standard extending vertically from said frame structure, a crane support 45 mounted on said standard for rotation on a vertical axis, a crane pivoted relatively to said crane support on a horizontal pivot carried by said crane support and having a load supporting arm at one side of its pivot relatively to said crane support, and a counterbalancing weight secured to said crane at the other side of its pivot relatively to said crane support for counterbalancing a load on said load supporting arm.
- 50 5. In a platform of the class described, a frame structure into which is adapted to enter the lifting mechanism of an industrial truck for lifting said frame structure, a standard extending vertically from said frame structure, a crane support 55 mounted on said standard for rotation on a vertical axis, a crane pivoted relatively to said crane support on a horizontal pivot carried by said crane support and having a load supporting arm at one side of its pivot relatively to said crane support, and a counterbalancing weight secured to said crane at the other side of its pivot relatively to said crane support for counterbalancing a load on said load supporting arm.
- 60 6. In a platform of the class described, a frame structure into which is adapted to enter the lifting mechanism of an industrial truck for lifting said frame structure, a standard extending vertically from said frame structure, a crane support 65 mounted on said standard for rotation on a vertical axis, a crane pivoted relatively to said crane support on a horizontal pivot carried by said crane support and having a load supporting arm at one side of its pivot relatively to said crane support, and a counterbalancing weight secured to said crane at the other side of its pivot relatively to said crane support for counterbalancing a load on said load supporting arm, said crane pivoting freely on said pivot until the load and counterbalancing weight are brought into balance.
- 70

6. In a platform of the class described, a frame structure into which is adapted to enter the lifting mechanism of an industrial truck for lifting said frame structure, a standard extending vertically from said frame structure, a crane support mounted on said standard and for rotation on a vertical axis, and a crane pivoted relatively to said crane support on a horizontal pivot carried by said crane support, and means for locking said crane support to said standard in any one of several rotated positions.

7. In a platform of the class described, a frame structure into which is adapted to enter the lifting mechanism of an industrial truck for lifting said frame structure, a crane support extending vertically from said frame structure, a crane pivoted relatively to said crane support on a horizontal pivot carried by said crane support and

having a load supporting arm at one side of its pivot relatively to said crane support, a counterbalancing weight secured to said crane at the other side of its pivot relatively to said crane support for counterbalancing a load on said load supporting arm, said crane pivoting freely on said pivot until the load and counterbalancing weight are brought into balance, and means for indicating the amount of pivotal movement of said crane required to bring said crane into balance.

10

15

8. In a platform of the class described, a pair of spaced floors between which is adapted to enter the load lifting portion of an industrial truck, a standard extending vertically between said floors and upwardly relatively to the upper of said floors, and a crane pivoted relatively to said standard about a horizontal pivot carried by said standard.

BRONISLAUS ULINSKI.
